BY Thomas F. Wallace

ATTORNEY

UNITED STATES PATENT OFFICE

134,291

DESIGN FOR A RING OR SIMILAR ARTICLE

Franklin E. Karples, Poundridge, N. Y.

Application October 8, 1942, Serial No. 108,469

Term of patent 3½ years

To all whom it may concern:

Be it known that I, Franklin E. Karples, a citizen of the United States of America, residing in Poundridge, county of Westchester, and State of New York, have invented a new, original, and ornamental Design for a Ring or Similar Article, of which the following is a specification, reference being had to the accompanying drawing, forming part thereof, wherein,

Figure 1 is a front elevational view of a ring or similar article showing my new design.

Figure 2 is a side elevational view of the ring or similar article shown in Figure 1.

I claim:

The ornamental design for a ring or similar article, substantially as shown.

FRANKLIN E. KARPLES.
